(57) **CLAIM**

The ornamental design for a vehicle front end, as shown and described.

DESCRIPTION

FIG. 1 is a front and right side perspective view of a vehicle front end showing our new design;

FIG. 2 is a front elevational view thereof;

FIG. 3 is a rear elevational view thereof;

FIG. 4 is a bottom plan view thereof;

FIG. 5 is a top plan view thereof; and,

FIG. 6 is a left side elevational view thereof.

It will be understood that the broken lines shown in the drawings illustrate portions of the vehicle front end that form no part of claimed design. The right side view is a mirror image of FIG. 6.
